HAIR WAVER

Filed Sept. 8, 1928

BY *John Hirschstein*
ATTORNEY

UNITED STATES PATENT OFFICE

JACOB A. BARRAKET, OF BROOKLYN, NEW YORK

HAIR WAVER

Application filed September 8, 1928. Serial No. 304,732.

This invention relates to hair wavers. More particularly it relates to a device for waving human hair, that may be clamped onto the hair to produce a waving effect without the use of heat.

An object of this invention is to provide a device of the character described which shall approximately fit the curved surface of the user's head, and

- 10 A further object is to provide a simple and rugged device of the character described which shall be cheap of manufacture and easy to manipulate, and shall yet be practical and efficient to a high degree in use.
- 15 Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawing, in which is shown one of the various possible illustrative embodiments of this invention,

Fig. 1 is a plan view of a hair waver embodying the invention;

Fig. 2 is an end view thereof;

Fig. 3 is a side view thereof;

Fig. 4 is a plan view showing a modified form of the device;

Fig. 5 is a cross-sectional view taken on line 5—5 of Fig. 4;

Fig. 6 is a partial plan view of the ridged plate used in the form shown in Fig. 1;

Fig. 7 is a perspective view showing the device applied to a woman's hair; and

Fig. 8 is a front view showing a portion of waves produced by the waver.

Referring in detail to the drawing, 10 designates a relatively thin matrix sheet or plate, of celluloid, aluminum, or other suitable material, die-formed to present a series of undulations. As illustrated, the plate 10 comprises elongated inwardly curved portions 11 and 12 joined by an outwardly curved portion 13 formed on a relatively smaller radius. 50 Outwardly curved portions 14 and 15 similar

to portion 13, extend from the outer edges of portions 11 and 12 respectively.

Said plate 10 is formed at one end thereof with bearing members 16 which receive the end post 17 of a forked member 18 for pivotally connecting the same to said plate. Said forked member 18 comprises prongs 19, 20, and 21 extending from said end post 17 and formed integrally therewith.

Said plate 10 and forked member 18 are slightly curved longitudinally as shown in Figs. 1 and 4 to form waves along downwardly curved lines. The plate and forked member may be curved convexly as at 22^a to a radius approximating the wearer's head.

Curved portions 13 and 14 of said plate 10 are provided with narrow slots 25 and 26 respectively extending substantially the length of the plate 10, but terminating short of the ends thereof. Prongs 19 and 20 of said forked member 18, are formed with curved, thin ribs 27, 28 adapted to extend thru said slots 25, 26 respectively when the forked member is swung toward said plate 10 to clamping position. The curvature of the outer edges 27^a, 28^a of said ribs 27, 28 is such that the mid-portions of said ribs are higher than the ends thereof.

Said plate 10 is provided with small loops 30 pivotally mounted on bearing member 31 formed integrally with said plate and in alignment with each of the prongs 19, 20, and 21. Thus when the forked member is swung toward the plate 10 or vice versa, the loop 30 may be pivoted to engage the ends 19^a, 20^a, and 21^a of said prongs 19, 20, and 21 respectively to maintain the device in clamped condition.

It will be noted that prong 21 is not provided with a rib extension as are prongs 19 and 20. Nor is curved portion 15 provided with a rib receiving slot as are curved portions 13 and 14. As clearly shown in Fig. 5, said prong 21 is formed to snugly fit into the groove formed by said curved portion 15.

In using the hair waver, the forked member 18 may be inserted into the hair, as closely to the scalp as possible in the manner of inserting a comb, the prongs being passed from the front of the head toward the back thereof.

The matrix plate 10 may then be swung toward the forked member 18, the prong 21 pressing the hair against curved portion 15 and the ribs 27 and 28 forcing bights of hair thru slots 25, 26 to form ridges 32, 33. The loops 31 may then be passed over the ends 19^a, 20^a, 21^a of the prongs to maintain the waver in clamped condition. In this condition the prong 21 acts as an anchor for the hair while the ribs 27, 28 push the hair thru the slots 25, 26. Due to the curvature of the ribs 27, 28 the ridges 32, 33 formed by said ribs, will be slightly higher in the middle than at the ends, as is clearly shown in Fig. 7.

15 The hair waver is provided with means for waving the hair in opposite directions. To this end the outer surfaces 35, 36 of portions 11, 12 are formed with small ridges 37, 38 respectively curved in opposite directions, as 20 clearly shown in Fig. 6. Thus each application of the clamp produces two concave waves curved upwardly at the ends thereof and generally conforming to the contour of the head. The hair in these waves undulates as shown in 25 Fig. 8 due to the oppositely curved ridges 37, 38 on the matrix plate 10. The hair ridges 32, 33 formed by the hair pushed thru the slots 25, 26 may be engaged between the fingers of the user and shaped and crimped as 30 desired in the manner of a finger wave.

Figs. 4 and 5 show a modified construction of the means for curving the hair in opposite direction. In accordance with this modification, the curved portions 11, 12 are provided 35 with central longitudinal slots 40, 41 for adjustably mounting curved sliding members 42, 43 on the outer curved surfaces of said portions 11, 12.

Said members 42, 43 are provided with 40 screw threaded stems 44, 45 respectively, extending thru said slots 40, 41 and receiving small finger nuts 44^a, 45^a. Loosening said nuts on said stems permits sliding adjustment of said members 42, 43. Said nuts 44^a, 45^a are 45 provided with shoulders 44^b, 45^b respectively, adapted to press against the portions 11, 12 to lock the members 42, 43 in any desired adjusted position.

Said sliding members 42, 43 are provided 50 with a plurality of spaced teeth 46, 47 respectively, integrally formed therewith, and adapted to engage the hair when the plate 10 is swung into clamping position. The members 42, 43 may then be adjusted and locked in 55 any position to curve the hair as desired. Thus the direction and amplitude of the curve of the waved hair may be changed to suit the will of the user.

It will be noted that no heat or electrical 60 appliances, injurious to the hair, need be used in connection with the waver herein described. In using the waver, the hair is preferably slightly moistened and combed before applying the device.

65 It will be understood further that the de-

vice may be formed to produce only one wave or a plurality of waves. For the purpose of illustration a hair waver for producing two rows of waves has been shown. Obviously, after one or more rows of waves has been 70 formed on the hair, additional rows may be produced by unclamping the device and applying it in suitable position adjacent the formed waves.

It will thus be seen that there is provided a 75 device in which the several objects of this invention are achieved, and which is well adapted to meet the conditions of practical use.

As various possible embodiments might be 80 made of the above invention, and as various changes might be made in the embodiment set forth, it is to be understood that all matter herein set forth or shown in the accompanying drawing, is to be interpreted as illustrative and not in a limiting sense.

Having thus described my invention, I 85 claim as new and desire to secure by Letters Patent:—

1. A hair waver of the character described comprising a transversely curved matrix plate providing a hair shaping surface and a forked member pivotally connected thereto, said plate being formed with at least one longitudinal slot, at least one of the prongs of 90 said forked member having a portion receivable in said slot.

2. A hair waver of the character described comprising a corrugated matrix plate of undulating cross-section, the surfaces of said plate curved in one direction being formed on a larger radius than the surfaces curved in the opposite direction, said surfaces formed on the smaller radius being slotted, and a forked member pivoted to said plate, said member having at least one prong formed with a portion adapted to extend thru said slot upon swinging said plate and member toward each other.

3. A hair waver of the character described comprising a corrugated matrix plate of undulating cross-section, the surfaces of said plate curved in one direction being formed on a radius larger than that of the curvature of the surfaces curved in the opposite direction, and a forked member pivotally connected to said plate, said member comprising prongs aligned with said second mentioned surfaces, at least one of said surfaces being formed with a slot, at least another of said surfaces being imperforate, at least one of said prongs being provided with a portion receivable in said slot, and at least another of said prongs being adapted to fit into the groove formed by said imperforate surface.

4. A hair waver of the character described comprising a corrugated matrix plate of undulating cross-section to provide curved hair shaping surfaces, said plate being curved to conform to a person's head and a pronged member pivotally connected to said plate, said 120 125 130

plate being provided with a slot, one of the prongs of said member being formed with a portion receivable in said slot for clamping hair to said surfaces.

5. A hair waver of the character described comprising a corrugated matrix plate of undulating cross-section providing hair shaping surfaces, said plate being generally curved to conform to a person's head, and a forked member pivotally connected to said plate, said plate being provided with a slot, one of the prongs of said member having a portion receivable in said slot, and a looped member pivotally connected to said plate engageable 10 with said prong to maintain said portion within said slot for clamping hair to said surfaces.

6. A hair waver of the character described comprising a matrix plate having a transversely curved hair forming surface and a longitudinally slotted surface extending therefrom, and a member movable relatively to said plate, said member having a prong formed with a portion receivable in said slot.

25. 7. A hair waver of the character described comprising a matrix plate having a curved hair forming surface and an oppositely curved slotted surface extending therefrom, and a forked member movable relatively to said plate, said member having a prong formed with a curved portion receivable in said slot, the curvature of said portion being such that the mid-section thereof is higher than the ends thereof.

35. 8. A hair waver of the character described comprising a corrugated matrix plate of undulating cross-section, the surfaces of said plate curved in one direction being formed on a radius larger than are the surfaces curved 40 in the opposite direction, and a forked member having prongs aligned with said second mentioned surfaces adapted to clamp hair to said plate, at least one of said second mentioned surfaces being formed with a slot, and 45 at least one of said prongs being formed with a rib-like portion receivable in said slot, and means on said first mentioned surface for undulating the hair transversely of the above mentioned cross-section.

50. 9. A hair waver of the character described comprising a corrugated matrix plate of undulating cross-section, the surfaces of said plate curved in one direction being formed on a radius larger than are the surfaces curved 55 in the opposite direction, and a forked member having prongs aligned with said second mentioned surfaces adapted to clamp a hair to said plate, at least one of said second mentioned surfaces being formed with a slot, and 60 at least one of said prongs being formed with a rib-like portion receivable in said slot, and manually adjustable means on said first mentioned surfaces for undulating the hair transversely of the above mentioned cross-section.

65. 10. A hair waver of the character described

comprising a matrix plate and a member pivotally connected thereto, said plate having a slot therein and said member having an upstanding portion adapted to register in said slot, said plate having a hair engaging surface which is curved transversely with respect to said slot.

In testimony whereof I affix my signature.
JACOB A. BARRAKET.
